PROCESS FOR PRODUCING DIBASIC CARBOXYLIC ACIDS

Edgar I. Crowley, Pittsburgh, Norman W. Franke, Penn Township, Allegheny County, and Ralph W. Helwig, Oakmont, Pa., assignors to Gulf Research & Development Company, Pittsburgh, Pa., a corporation of Delaware

Application May 3, 1955, Serial No. 505,602

1 Claim. (Cl. 260—452)

This invention relates to an oxidation process for converting saturated aliphatic hydrocarbons to organic acids and more particularly to an oxidation process for converting saturated aliphatic hydrocarbons to dibasic carboxylic acids.

Saturated aliphatic hydrocarbons, such as paraffin wax, can be oxidized with nitric acid under controlled conditions to produce a product comprising dibasic carboxylic acids. The amount of oxidant generally needed in such a process to obtain satisfactory yields of dibasic carboxylic acids is unusually high, and methods have therefore been sought to increase the yield of dibasic carboxylic acids for the same amount of nitric acid employed. One method of reducing the consumption of nitric acid involves preoxidizing the charge stock comprising a saturated aliphatic hydrocarbon with air and thereafter subjecting at least a portion of the oxidation product obtained to further oxidation with nitric acid. Further reduction in the consumption of nitric acid involves employing reaction conditions in the nitric acid reaction stage that permits most effective use of the oxidants available in said stage.

We have found that the oxidation of saturated aliphatic hydrocarbons can be improved and the amount of dibasic carboxylic acids produced therefrom can be increased by a process which comprises oxidizing a composition consisting essentially of saturated aliphatic hydrocarbons with air or other gas containing molecular oxygen, subjecting at least a part of the oxidation product obtained to further oxidation with nitric acid to obtain a mixture comprising a nitric acid phase and an oil phase, washing said oil phase with water, and thereafter recovering dibasic carboxylic acids from said nitric acid phase and said water wash.

Saturated aliphatic hydrocarbons boiling above about 250° F. and having about eight or more carbon atoms or mixtures thereof can be employed as charge stock for the production of dibasic acids in accordance with our process, although, for ease of operation, we prefer to employ saturated aliphatic hydrocarbons having from about 10 to about 40 carbon atoms. Included among the saturated aliphatic hydrocarbons which can be employed in our process are petroleum waxes, paraffinic oils, foots oil, oils and waxes obtained from the Fischer-Tropsch process, n-octane, decane, cetane, etc. While we prefer to employ charge stocks consisting of saturated aliphatic hydrocarbons, we can also employ charge stocks which are predominantly saturated aliphatic hydrocarbons and which can contain cycloparaffins. Such charge stocks can be prepared from a variety of types of crude oils. When the crude oil is essentially paraffinic, the charge may be recovered by distillation but where the crude oil is of a mixed type, various combinations of treatments can be employed to obtain the charge, such as distillation and solvent extraction, distillation and crystallization, or chromatographic separation.

Oxidation of saturated aliphatic hydrocarbons with air or other gas containing molecular oxygen in the

2

first stage of our process can be conducted satisfactorily either at atmospheric or elevated pressures. While pressures as high as about 1000 pounds per square inch gauge can be employed without affecting adversely the oxidation reaction, we prefer to employ pressures ranging from about atmospheric to about 150 pounds per square inch gauge. The temperature of the air oxidation reaction is not critical and can be varied over a great range. Thus, a temperature of about 100° to about 400° C. is satisfactory, although a temperature of about 150° to about 190° C. is preferred. In order to cut down on the nitric acid consumption in the second stage of our process, the saturated aliphatic hydrocarbon should be oxidized for a time sufficient to obtain an air oxidation product having a saponification number above about 100, and preferably about 150 to about 450. While the time required to obtain an air oxidation product having the desired saponification number is, of course, dependent upon a number of variables, a period of about 2 to about 20 hours is generally sufficient. The amount of molecular oxygen required to obtain the air oxidation product is not critical and an excess is desirable, although about 0.5 gram to about 2.0 grams of oxygen per gram of charge is sufficient.

25 The air oxidation product obtained in the first stage or a fraction thereof is thereafter passed to a second stage where it is oxidized with nitric acid. While the amount of nitric acid employed in the nitric acid stage is not critical and can be varied over a wide range, provided sufficient acid is present for the desired oxidation, charging about 2.5 to about 20 parts of nitric acid per part of air oxidation product to the nitric acid reaction zone is sufficient to obtain the desired dibasic carboxylic acids.

35 The pressure in the nitric acid reaction zone is similarly not critical and can be varied over a wide range, a pressure of about atmospheric to about 1500 pounds per square inch gauge being preferred. For best results we operate the nitric acid reaction at a temperature of about 50° to about 150° C. preferably at a temperature of about 75° to about 130° C. The residence time for the saturated aliphatic hydrocarbon in the nitric acid necessary to obtain substantial amounts of dibasic carboxylic acids varies inversely with temperature. For example, about the same amount of reaction is obtained in a period of about 30 hours at 75° C. as is obtained in less than about two hours at 130° C. The reaction can be carried out at a constant temperature or the temperature can be varied with time. Thus, the reaction can be started at a low temperature, say 50° C., and the temperature gradually raised to a selected maximum temperature and the reaction can be discontinued when the maximum temperature is reached, or the reaction can be maintained at the selected maximum temperature for the desired length of time.

55 During the oxidation of the air-oxidized products of saturated aliphatic hydrocarbons with nitric acid, the acid breaks down to form NO₂, NO, N₂O, nitrogen and some water. Additional water is present in the nitric acid reaction zone as the result of the oxidation of the air-oxidized products of saturated aliphatic hydrocarbons and, of course, since an aqueous solution of nitric acid is employed, some water is introduced into the nitric acid reaction zone with the acid. NO₂ dimerizes to form N₂O₄, which is in equilibrium with NO₂. NO₂, as well as N₂O₄, has been found to be an excellent oxidizing agent for air-oxidized products of saturated aliphatic hydrocarbons. Therefore, if the nitric acid reaction stage, or second stage, of our process is conducted in a container such that NO₂ formed during the process is prevented from escaping, NO₂ will react with the air-oxidized products of saturated aliphatic hydrocarbons in the nitric

acid reactor. In addition, in the absence of substantial amounts of oxygen in the nitric acid reactor, NO formed will react with NO_2 to form N_2O_3 , which is also believed to be an excellent oxidizing agent for air-oxidized products of saturated aliphatic hydrocarbons. At the same time, NO_2 and N_2O_3 will react with the water present to form nitrous as well as nitric acid, both of which are believed to be excellent oxidizing agents for the purpose of this invention. In this way, by utilizing NO_2 , NO, water, other nitrogen oxides and nitrogen acids formed during the process as oxidants, the amount of nitric acid necessary in the second stage of our process for converting air-oxidized products of saturated aliphatic hydrocarbons to dibasic acids is substantially reduced.

In order to cut down on the amount of nitric acid consumed in the second stage of our process, gaseous oxygen can be added directly to the nitric acid reactor or evolved nitrogen oxides, except N_2O , can be regenerated in a second vessel adjacent thereto. The amount of air or other gas containing molecular oxygen added to the nitric acid reactor or necessary to regenerate the nitrogen oxides is not critical and can be varied over a wide range, although we prefer to use more than the theoretical amount to insure adequate regeneration. For example, about 30 to about 100 grams of oxygen per 100 grams of air oxidation product of saturated aliphatic hydrocarbon and 500 grams of 70 percent nitric acid are sufficient for purposes of regeneration or introduction into the nitric acid reaction zone.

When oxygen is introduced into the nitric acid reactor, a smaller amount of nitric acid is lost by conversion to nitrogen or N_2O than if no oxygen were introduced to the reactor. If the exhaust gases are passed to a separate vessel where the nitrogen oxides, except N_2O , are regenerated with gaseous oxygen to higher oxides of nitrogen, nitrous acid and nitric acid, and these materials allowed to return to the nitric acid reactor, a substantial saving in the amount of nitric acid converted to nitrogen and N_2O is found. As stated, with no substantial amounts of oxygen in the nitric acid reactor, NO, NO_2 , as well as N_2O_3 , are formed and these are passed to the regenerator. NO_2 remains unaffected by the presence of oxygen but NO and N_2O_3 are regenerated by the oxygen to NO_2 . The NO_2 already present, as well as the NO_2 formed in the regenerator, is condensed therein and recycled to the nitric acid reactor where the NO_2 reacts with the air-oxidized products of saturated aliphatic hydrocarbons as such or is converted by reaction with water to nitric acid. In the regenerator the NO_2 can combine with water to form nitric acid which is recycled to the nitric acid reactor.

At the end of the nitric acid reaction the oxidation product obtained comprises an upper oil-phase layer and a lower nitric acid layer. The upper oil-phase layer can vary from about 5 to about 50 percent by weight (based on the air oxidation charge) and usually comprises a mixture of C_4 to C_{12} dibasic carboxylic acids and C_6 to C_{20} monobasic carboxylic acids. The nitric acid layer contains unreacted nitric acid as well as dibasic carboxylic acids having from 3 to about 12 carbon atoms. We have found that the amount of dibasic carboxylic acids recovered in the two stage oxidation of saturated aliphatic hydrocarbons can be further increased by washing the oil-phase layer with water and thereafter additionally recovering dibasic carboxylic acids from said water wash.

In carrying out the washing step, the oil-phase layer is separated from the nitric acid layer and is washed with at least one-half times and preferably about one to about 2 times its volume of water. The wash water containing the water soluble constituents of the oil-phase layer, including the mixture of C_4 to C_{12} dibasic carboxylic acids, is thereafter combined with the mixture of dibasic carboxylic acids of the nitric acid layer and the resulting mixture is then subjected to distillation to remove therefrom water and any nitric acid which may

be present. The water washing is effective for several reasons. It succeeds in removing the water-soluble acids, including dibasic carboxylic acids, from the oil-phase layer. In addition, the wash water is then used in stripping nitric acid from the organic acids present in the nitric acid layer. Moreover, it permits the major proportion of water-soluble acids extracted from the oil phase by water washing to be purified together in the same recovery system.

10 A method of carrying out our invention employing a first stage air oxidation, a second stage nitric acid oxidation, wherein the second stage of the process is conducted in a closed container and the nitrogen oxides formed therein are regenerated in a separate regenerator and 15 recycled to the second stage of the process, and the step of washing a portion of the oxidation product obtained in the nitric acid reactor is illustrated in the single drawing which describes a flow diagram of such typical procedure. For simplicity, valves, gauges, etc., not needed 20 for an understanding of the invention have been omitted. The drawing is hereby incorporated in and made a part of the present specification.

A saturated aliphatic hydrocarbon is charged into oxidation reactor 2 by line 4 and a gas containing molecular oxygen such as air by line 6. The saturated aliphatic hydrocarbon is vigorously agitated at an elevated temperature in reactor 2 for a time sufficient to obtain an oxidation product having a saponification number above about 100 and preferably about 150 to about 450. In order to facilitate the oxidation in reactor 2, a catalyst such as vanadium pentoxide can be employed. Volatilized lower molecular weight products produced during the air oxidation step are removed overhead from reactor 2 and passed to condenser 8 by line 10. The condenser is preferably maintained at a temperature of about 35° to about 90° F. by any suitable means, although any temperature sufficient to condense a large part of the volatilized lower molecular weight products can be employed. The condensed lower molecular weight products in condenser 8 30 resolve themselves into two phases, an upper organic phase comprising oxidized hydrocarbons, including lower organic acids, esters and aldehydes, and a lower aqueous phase comprising formic, acetic and propionic acids, and are removed from condenser 8 by line 12. Uncondensed 35 lower molecular weight products comprising excess air, nitrogen, carbon monoxide and carbon dioxide are removed from condenser 8 by line 14.

The air oxidation product is removed from reactor 2 by line 16 and passed to nitric acid reactor 18, and nitric acid is led to reactor 18 by line 20. The pressure in reactor 18 is maintained at an elevated pressure. The nitric acid reactor can be a stainless steel pressure vessel equipped with a stirrer, and in the instant embodiment, is provided with a nitrogen oxide regenerator 22. The air oxidation product and nitric acid are heated in reactor 18, by means not shown, and stirred. If desired, reactor 18 can be operated continuously, in which case a coil-type reactor or one vessel or a number of vessels in series can be employed. Nitrogen oxides formed during the process are removed overhead from reactor 18 by line 24 and passed to nitrogen oxides regenerator 22. A controlled amount of air or other gas containing molecular oxygen is introduced in the regenerator by line 26 and, as noted, N_2O_3 and NO are regenerated therein to NO_2 which, along with the NO_2 already present, is condensed therein and recycled by line 28 to reactor 18. The pressure in regenerator 22 is of the same order as that existing in reactor 18 and the temperature is sufficiently low, from about 0° to about 120° F., preferably about 20° to 90° F., so as to enable the NO_2 in the gases to condense and be returned to reactor 18. N_2 , N_2O , CO and CO_2 , as well as oxygen-containing regenerating gas, are removed overhead from regenerator 22 by line 30.

After sufficient residence time in reactor 18, the oxidation product is removed from the reactor by line 32

and passed to separator 34 which is maintained at a temperature of about 40° to about 110° F., preferably about 70° to about 90° F., where it separates into an upper oil-phase layer and a lower nitric acid layer. The upper oil-phase layer can vary from about 5 to about 50 percent (based on the air-oxidation product charged to reactor 18), and usually comprises a mixture of C₄ to C₁₂ dibasic and C₈ to C₂₀ monobasic carboxylic acids. The oil-phase layer is removed from separator 34 by line 36 and passed to a washer 38. Water is introduced into washer 38 through line 40 and is intimately mixed with the oil-phase layer therein. Washing of the oil-phase layer need not be effected in a single stage but can be carried out in a plurality of stages. The resulting mixture in washer 38 resolves itself into two phases, an upper oil-phase, substantially free of water-soluble acids, which can be recycled by line 42 to either air oxidation reactor 2, nitric acid reactor 18 or both, and the water wash which is removed by line 44 and passed to evaporator 46.

The nitric acid layer is removed from separator 34 by line 48 and passed to vacuum still 50. Nitric acid is removed overhead from vacuum still 50 by line 52 and can be sent to an absorption tower, where the nitric acid can be reconcentrated with fresh NO₂ and air, or can be sent to a distillation zone where it can be reconcentrated by distillation. The temperature and pressure in vacuum still 50 are not critical and can vary from a temperature of about 80° to about 200° F. and a pressure of about 0.5 to about 20 inches of mercury. If desired, nitric acid so obtained and so reconcentrated can be recycled to line 20 for use in reactor 18.

The residue from vacuum still 50, comprising a slurry of solid and liquid acids, is removed from the still by line 54 and passed to evaporator 46 where it is combined with wash water entering through line 44. The evaporator is maintained at a suitable temperature, about 100° to about 230° F., and a suitable pressure, about 0.5 to about 29 inches of mercury, effective to remove from the mixture therein substantially all of the water and the nitric acid not previously removed in vacuum still 50 and present with the dibasic carboxylic acids in the evaporator. The mixture of water and nitric acid is removed overhead from evaporator 46 through line 56 and discharged. Instead of employing both a vacuum still 50 and an evaporator 46 in the procedure above, we can pass both the nitric acid phase and the wash water in line 44 to a single unit wherein the nitric acid and the water can be removed by suitable distillation or evaporation procedures. Thus, the nitric acid phase can be combined with the wash water and the whole subjected to distillation or evaporation, or the nitric acid phase can initially be subjected to distillation or evaporation procedures, after which the residue can be combined in the same unit with the wash water and the resulting mixture can be treated to remove water and nitric acid therefrom.

The residue from evaporator 46 comprising a slurry of solid and liquid acids is removed therefrom by line 58 and passed to cooler 60. The slurry is cooled in cooler 60 to a suitable low temperature, preferably to a temperature of about 65° to about 75° F. and allowed to stand therein to permit the crystallization of the dibasic acids present.

The mixture of dibasic carboxylic acids obtained in cooler 60, comprising C₃ to C₁₀ dibasic acids, can be used as such or can be subjected to further treatment. Thus, the mixture can be discharged from cooler 60 through line 62 and passed to filter 64. The filtrate from this filtration step is removed by line 66 and passed to line 68 and after sufficient filter cake has formed in filter 64, filtration is stopped and the cake is washed with benzene from line 70. If desired, the mixture of dibasic carboxylic acids obtained in cooler 60 can be slurred with one to about 5 parts of benzene and the slurry then filtered. The filter cake can thereafter be washed with benzene. The benzene washings are re-

moved from filter 64 by line 72 and passed to stripper 74. Benzene is removed overhead from stripper 74 and recycled by line 76, and that remaining from the benzene washings not going overhead in line 74 is passed to line 68. The filter cake, after the benzene washings, is transferred to dryer 78 by conveyor line 80. In dryer 78 any benzene present in the filter cake is removed overhead by line 82 and recycled to line 70 by means of line 76. The residue from dryer 78 is removed therefrom by conveyor line 84 and comprises a mixture of aliphatic dibasic carboxylic acids.

To the filtrate and residue remaining from the benzene washings in line 68 is added any solvent or diluent which has a preferential attraction for any monobasic acids present, such as diethyl ether, ethylpropyl ether, dipropyl ether, dimethyl ether, benzene, carbon tetrachloride, ethyl carbonate, chloroform, trichloroethylene, etc., through line 86, and the resulting solution is passed upwardly into the base of extraction chamber 88. We have found that diethyl ether is especially effective in our process, and our discussion will be with reference to it. Water or dilute aqueous solution of a mineral acid such as hydrochloric acid, nitric acid, etc., is introduced into the top of chamber 88 by line 90 and is mixed therein with the solution entering from line 68 resulting in a lower aqueous phase and an upper ether phase.

The aqueous phase is removed from the base of chamber 88 by line 92 and passed to stripper 94. Water is stripped from the aqueous phase in stripper 94 and removed overhead by line 96, while a mixture comprising aliphatic dibasic carboxylic acids is removed by line 98. Water in line 96 is passed to separator 100, wherein water is removed by line 102 and any ether which may have been carried by the water is removed by line 104 and recycled to line 86.

The ether phase is removed overhead from chamber 88 by line 106 and passed to stripper 108, wherein ether is removed by line 110 and recycled to line 86 by line 104, and a complex mixture comprising higher dibasic carboxylic acids, monobasic acids and nitrogen containing acids is removed by line 112. If desired, the acids removed in line 112 can be recycled to either air oxidation reactor 2, nitric acid reactor 18, or both.

The product obtained in line 84 comprises a mixture of aliphatic dibasic carboxylic acids containing from about 4 to about 10 carbon atoms, predominantly acids having an even number of carbon atoms, and the product obtained in line 98 comprises a mixture of aliphatic dibasic acids containing about 3 to about 9 carbon atoms per molecule, predominantly acids having an odd number of carbon atoms.

The following examples illustrate the increased yields obtained by carrying out the two-stage oxidation of saturated aliphatic hydrocarbons in accordance with our invention.

EXAMPLE I

500 grams of Gulfwax (a refined paraffin wax having a melting point of 133° F.) was oxidized in air at a temperature of 160° C. by blowing therethrough 2.5 liters of air per minute per kilogram of wax and 475 grams of an oxidation product having a saponification number of 221 was obtained. Into a continuous autoclave was fed the 475 grams of air oxidation product, 1412 grams of 65 percent aqueous nitric acid and 315 grams of oxygen. The pressure was maintained at about 500 pounds per square inch gauge, the temperature at 130° C. and the contact time was 30 minutes. The product obtained comprised a two-phase liquid product consisting of 1406.8 grams of nitric acid phase and 223.9 grams of oil phase. The oil phase was washed three times, each time with 150 milliliters of distilled water at about 90° C., the washings settled and decanted after cooling after each wash giving three oil phase washings. The washed oil was then heated for several hours in

an open beaker over a water bath to evaporate dissolved water yielding 185.3 grams of oil phase acids.

The nitric acid phase was divided into two equal portions which were separately worked up in the following manner identically except that with portion "A" the oil phase washings were employed as the following described nitric acid chasers while with portion "B" similar volumes of fresh water were used as chasers.

The nitric acid phase was placed in a distillation flask and nitric acid distilled off at a pot temperature of 35 to 45° C., the temperature being regulated by the degree of vacuum maintained on the system, the pressure being adjusted around 30 mm. Hg. Near the end of the distillation as the pot temperature began to increase, the pressure was gradually lowered to about 5 mm. Hg and the temperature was then permitted to increase to 50° C. at which point the distillation was stopped. In portion "A" the first oil phase wash was added to the residue in the still pot and distillation was resumed under conditions similar to the main distillation. Distillation was again stopped at a pot temperature of 50° C. at 5 mm. Hg. This constituted the first nitric acid chaser. Similarly the second and third oil phase washes were added and distilled off. In portion "B" the nitric acid chasers consisted of three 150 ml. portions of distilled water. The final residue of crude dibasic acids remaining in the pot was weighed, transferred to a beaker, and intimately contacted with two-thirds its weight of benzene. The resulting slurry was filtered and the precipitate returned to the beaker and re-washed with same quantity of benzene and again filtered. This procedure was repeated once more. After the final filtration, the precipitate was spread on paper and the residual benzene permitted to evaporate to the air. The dried solids were weighed as "precipitated acids." The benzene filtrates were combined and placed over a water bath until substantially all of the benzene had evaporated leaving a "wash oil" which was dissolved in 3 ml. ether per gram of oil and the resulting solution was extracted three times each with a volume of water equal to the volume of ether used to dissolve the "wash oil." The water was then evaporated from the aqueous extract phases and the ether from the raffinate phase yielding "extracted acids" and "raffinate acids," respectively. The following table indicates the yields of products obtained, the figures being parts per hundred parts of air-oxidized wax charged to the nitric acid stage. Correction has been made for the fact that oil phase washings from the total oil phase were used in working up only one half of the nitric acid phase.

Table I

Products	Portion A (Oil Phase Washings)	Portion B (Distilled Water)
Intermediate: Crude Dibasic Acids (Distillation Residue)	60.50	54.10
Final: Precipitated Dibasic Acids	20.35	19.40
Extracted Dibasic Acids	17.96	16.52
Total Dibasic Acid Fraction	38.31	35.92
Raffinate Acids	17.15	15.20

EXAMPLE II

861.5 grams of an oxidized wax mixture consisting of 322.5 grams of oil phase acids recovered from a previous nitric acid stage oxidation of air oxidized deoiled foots oil and 539.3 grams of a 234 saponification number air oxidized deoiled foots oil obtained by blowing 576 grams of deoiled foots oil for eleven hours at 160° C. with 2.5 liters of air per minute per kilogram of wax were continuously passed to a continuous autoclave together with 2530 grams of 65.6 percent aqueous nitric acid and 2140

75

liters (standard temperature and pressure) of air. The pressure was maintained at about 500 pounds per square inch gauge, the temperature at 130° C. and the contact time was 30 minutes.

Products from this nitric acid stage oxidation were worked up in a fashion similar to that of the previous example. In this example isopropyl ether was employed in working up the crude DBA (Distillation Residue) rather than benzene and ether as in the previous example. In this instance isopropyl ether was used to wash the crude acids three times, each time with a weight of isopropyl ether equal to one-third the weight of the original crude acids. The combined isopropyl ether filtrates were then extracted with water three times each time using a weight of water equal to the weight of the combined filtrates. The nitric acid phase was divided into two equal portions and each worked up separately and in the same manner except that with one portion the aqueous washings of the oil phase were used as nitric acid chasers while with the second portion fresh water was used as nitric acid chasers. In this run 433 grams of oil phase was recovered and washed three times, each with 200 ml. of water at about 90° C. Separation of the aqueous washes resulted in recovery of 222.4, 176.0, and 166.1 grams of oil phase washes half of which were used in turn as the 1st, 2nd, and 3rd chasers in the one case. Identical quantities of distilled water were used as the chasers in the other case.

The product yields (part per 100 parts of oxidized wax charged to the nitric acid stage) for these procedures were calculated as indicated below in Table II.

Table II

Products	Portion A (Oil Phase Washings)	Portion B (Distilled Water)
Intermediate: Crude Dibasic Acids	57.1	52.3
Final: Precipitated Dibasic Acids	12.6	12.2
Extracted Dibasic Acids	20.6	18.5
Total Dibasic Acid Fraction	33.2	30.7
Raffinate Acids	17.3	15.4

The increased yields of dibasic carboxylic acids obtained by the simple expediency of washing the oil phase layer obtained in the nitric acid reactor with water and further treating the water washings obtained is shown in each of the tables. In Table I, the yield of the purified dibasic acid fraction was increased by 6.7 percent, while in Table II the increase in yield amounted to 8.2 percent. The raffinate acids obtained in the process are a mixture of dibasic and nitrogen-containing organic acids which can be employed as such as chemical intermediates. In Table I the increase in yield of raffinate acids amounted to 12.8 percent, while in Table II the increase amounted to 12.3 percent.

Obviously, many modifications and variations of the invention, as hereinabove set forth, can be made without departing from the spirit and scope thereof, and therefore only such limitations should be imposed as are indicated in the appended claim.

We claim:

A process for the production of dibasic carboxylic acids from a charge stock consisting essentially of saturated aliphatic hydrocarbons boiling above about 250° F. and having at least 8 carbon atoms which comprises subjecting the charge stock to oxidation with a gas containing molecular oxygen for a time sufficient to obtain a product having a saponification number above about 100 but below about 450, subjecting said product to further oxidation at an elevated temperature with nitric

acid to obtain a product comprising a nitric acid phase containing nitric acid and dibasic carboxylic acids and an oil phase carrying dissolved dibasic carboxylic acids, separating said nitric acid phase and said oil phase, washing said oil phase with water, removing unreacted nitric acid from said nitric acid phase to obtain a product containing dibasic carboxylic acids, combining said latter product and said water wash, removing water and additional nitric acid from the resulting mixture, and thereafter recovering dibasic carboxylic acids from the resulting mixture. 10
